PAIR OF SPECTACLES

Victor Harrap, Elkins Park, Pa.

Application December 30, 1954, Serial No. 33,743

Term of patent 14 years

(Cl. D57—1)

3

FIG.1

FIG.3.

FIG.2

Fig. 1 is a perspective view taken from the front of a pair of spectacles showing my new design; and

Fig. 2 is a perspective view taken from the rear thereof.

Fig. 3 is a cross-sectional view thereof, taken along the line 3—3 of Fig. 1.

The dominant feature of my design resides in the portions shown in full lines.

I claim:

The ornamental design for a pair of spectacles, as shown and described.
